UNITED STATES PATENT OFFICE.

HUGH F. HURST, OF RICHMOND, VIRGINIA, ASSIGNOR TO HURST LABEL PRINTING MACHINE COMPANY, INCORPORATED, A CORPORATION OF VIRGINIA.

PRINTING AND STAMPING MACHINE.

1,426,069.

Specification of Letters Patent. Patented Aug. 15, 1922.

Application filed May 7, 1921. Serial No. 467,639.

To all whom it may concern:

Be it known that I, HUGH F. HURST, a citizen of the United States, residing at Richmond, in the county of Henrico and State of Virginia, have invented certain new and useful Improvements in Printing and Stamping Machines, of which the following is a specification, reference being had to the accompanying drawings.

10 In the art of printing, a patent has been granted to the aforesaid Hugh F. Hurst for a machine for printing and stamping labels particularly those used by druggists, therefore the purpose of the present invention is 15 to improve, simplify, and render more practical for commercial purposes, the type of machine set forth, illustrated and claimed in the Patent No. 1,374,374 issued April 12, 1921.

20 Another purpose embodies a machine of this character wherein the printing cylinder or die has its impression type fastened thereon by removable fastening devices, instead of dovetailing the type in the cylinder 25 or die, and also wherein the brake for retarding the cylinder is disposed exteriorly of the casing, instead of interiorly.

Another purpose is to improve the general construction of this character of machine, for the reason that subsequently to 30 various experiments it has been found that the present construction herein shown is of commercial value.

In the present type of machine it is the 35 purpose to impress the label against the printing cylinder or die with the ribbon therebetween, in lieu of depressing the cylinder, thereby avoiding jarring the parts of the machine, as well as mutilating or mashing 40 the type and also more or less injuring the ribbon, which are more or less the disadvantages of the former machine disclosed in the aforesaid patent.

Still another purpose is to provide a machine of this character, wherein the label feed is actuated by the same mechanism which impresses the label toward the type of the cylinder, with the ribbon therebetween.

50 A further purpose involves the provision of a single means for simultaneously actuating a ribbon escapement feed, and a label feed, and also impresses the label and the ribbon toward the type of the printing cylinder or die, thereby simplifying and ren-

dering more practical the general construction of the type of machine in said patent.

Additionally the invention aims to provide means for not only printing the name of the medicine on the label, but also printing the name of the druggist, thereby avoiding considerable expense to the druggist, in having labels printed by a printer which is more or less expensive.

As in the aforesaid patent it is the aim of the present invention to print upon druggists' labels the name of the medicine, such as "Essence of Lemon," "Alcohol 90 percent," "Spirits of Camphor," "Bay Rum," etc., at the time the label is to be used, thereby avoiding having stock labels printed in quantities, and kept in compartments of a large drawer, as is the present method. The present form of machine also avoids writing the name of the medicine on blank labels as they are used, for it is obvious that all is required, is to impart an impression movement to the actuator of the machine, causing the label to be instantly printed and fed sufficiently out from the machine, whereby it may be withdrawn the remaining distance, and cut off.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts as will be herein-after set forth, shown in the drawings and claimed.

95 In the drawings:

Figure 1 is a view in side elevation of the improved label printing and stamping machine constructed in accordance with the invention.

Figure 2 is a view in elevation at right angles to that shown in Figure 1.

Figure 3 is a sectional plane view on line 3-3 of Figure 1.

Figure 4 is a view in elevation of the opposite side of the label printing and stamping machine, more clearly showing the label cutting knife.

Figure 5 is a detail sectional view of a portion of the casing of the machine, show-

ing one of the label feeding means, to insure feeding the label from the machine subsequently to its having been printed or stamped.

5 Figure 6 is a detail perspective view of the escapement feed for the ribbon, also showing the dog for also feeding the label.

10 Figure 7 is a detail view in elevation of the means exteriorly of the casing of the machine for feeding the label, as well as rotating the impression roll of the printing mechanism which prints the name of the druggist.

15 Figure 8 is a detail perspective view of the label severing knife.

Figure 9 is a detail perspective view of a portion of the lever which actuates and imparts an impression movement to the label and ribbon.

20 Figure 10 is a detail perspective view of the lever 88.

Figure 11 is a detail view of the spring retained dog 30, showing the shoulder 32.

25 Figure 12 is a detail view of a fragmentary portion of the cylinder 36 and the angular extension 34 to show how the names of the stock medicines are indicated.

30 Figure 13 is a detail view of a portion of the cylinder 9, showing the different names of the medicines on the plates, which are fastened to the cylinder by screws.

35 Referring to the drawings, the machine comprises a base 1, which has an upstanding rectangular flange 2. The opposite longitudinal sides of this flange are connected by medial upstanding rectangular flanges 3, which are spaced to form a cavity 4 for the reception of a label impression member or platen 5, which carries a rubber strip 6, 40 which is of sufficient hardness, as to cause a proper impression of the label on the type of the cylinder or die. The base with its upstanding flange 2 and the spaced flanges 3 are preferably constructed in a single casting, though it may be otherwise formed.

45 A housing 7 is hingedly mounted on the upstanding flange 2 at one end of the base, and is of a shape corresponding to and adapted to receive a printing cylinder or die 9. The shaft or pintles 10 of the cylinder or die 9, are mounted in bearings of the housing 7, therefore it is obvious that when the housing is open, the cylinder or die moves therewith.

55 One of the longitudinal walls of the flange 2 is provided with a depression 11, which protrudes inwardly of the casting, particularly where the flanges 3 connect.

60 Arranged transversely of the base and between the longitudinal sides of the flange 2 are ribbon carrying rolls 12 and 13, which have longitudinally extending slots 14, in which the ends of the ribbon may be attached, so as to anchor the ribbon to the rolls. After the ends of the ribbon have

been inserted in the slots, the rolls may be rotated sufficiently for the ribbon to wind a couple of times on one or the other of the rolls, while the greater portion of the ribbon is rolled on the other roll. The rolls 12 and 13 have certain corresponding ends provided with reduced shaft extensions 16, which are mounted in bearings of one of the longitudinal sides of the flange 2, and fastened by means of pins or the like 17 to 70 the shaft extensions are ratchet wheels 18 and 19. The other ends of the rolls 12 and 13 have bores 20, which receive the ends of the shanks of screws 21, which engage through one of the longitudinal portions of 80 the flange 2. The screws 21 are threaded through the flange 2, and surrounding their shanks are coiled springs 22, which are interposed between the flange 2 and the ends of the rolls. These flanges are provided for 85 the purpose of bearing against the ends of the rolls to insure friction, for the purpose of holding the rolls in place, especially in order to prevent displacement of the ribbon, after having once been adjusted or 90 moved subsequently to the movement of the platen surface. In view of this construction it will be noted that the present type of machine eliminates the provision of the additional dogs and the additional ratchet 95 wheels, which are embodied in the aforesaid patent, thereby simplifying this form of printing and stamping machine.

The printing cylinder or die 9 is provided with a plurality of flat faces 23, to 100 which the type plates 24 are fastened in any suitable manner, preferably by means of screws 25. Obviously the type plates can be removed, repaired or replaced by others. It is also obvious that the cylinder or die 105 may be made any diameter whatever, so as to accommodate most any number of type plates.

One end of the cylinder or printing die shaft 10 carries a cylindrical drum 26, on 110 the cylindrical surface of which the names of various medicines, such as camphor, essence of lemon, spirits of niter and the like are carried. This drum 26 has a hand piece 27, by which the drum may be rotated, it 115 also being possible to rotate the cylinder or die at the same time, so as to set the proper type plate or bar in position to receive the impression of the paper thereon.

Also movable with the drum 26 is a 120 toothed wheel 28, and mounted in guides 29 is a dog 30, there being a coiled spring 31 surrounding the detent dog 30 and interposed between one of the guides 29 and a shoulder 32 of the detent dog, thereby holding the nose thereof in engagement with the teeth of the toothed wheel 28, for the purpose of holding the drum as well as the printing cylinder or die in different adjusted positions while an impression of the 130

label is being made. Connecting the ends of the guides 29 is a plate 33 having at its lower end an extension 34 which holds at right angles to the body of the plate. This 5 extension 34 has a U-shaped opening 35 through which the names of the medicines on the drum can be seen, as they pass the extension. In fact the names of the medicines to be printed on the labels correspond 10 to those on the cylinder or die, and those on the drum are arranged diagonally opposite those on the cylinder or die. For instance supposing spirits of camphor on the drum is appearing through the U-shaped 15 opening 35, then the title, spirits of camphor on the cylinder or die will be facing downwardly, so as to receive the impression of the label and the ribbon there against. Therefore, when the druggist desires the 20 label having the words "spirits of niter" thereon, the drum may be rotated, until spirits of niter appear through the U-shaped opening, then the impression on the label and the ribbon may be made.

25 Projecting from one side of the housing 7 is a lug 36 and guided thereon and on one end of the shaft 10 is a detent escapement 37. In fact the detent escapement comprises a vertically extending plate 38 provided with laterally disposed arms 39 at its lower end. The plate has a slot 40 in its upper portion through which the shaft 10 of the cylinder or die extends, while the lower part of the plate is slotted from the 35 arms 39 upwardly almost to the slot 40. The lug or pin 36 engages the lower part of the slot 41, so as to guide the escapement detent in its upward movement. A spring 42 is connected to the pin 36, and is in 40 turn connected to the crotch of the slot 41, thereby tensioning the escapement detent in such wise as to cause the upper end of the slot to normally rest on the shaft 10. Pivotally mounted on the ends of the arms 39 are detent dogs 43, the noses 44 of which engage with the teeth of the ratchet wheels 19, which are carried by the shaft extensions of the ribbon rolls 12 and 13. One of the arms 39 has a depending extension or leg 50 45, to the lower end of which a lug 46 is connected. Projecting laterally from the depending extension or leg 45 is a pair of lugs 47, between the ends of which as at 48 a dog 49 is pivoted. A spring 50 is interposed between the dog 49 and the extension or leg 45. Suitable projections 51 and 52 are carried respectively by the extension 45 and the dog 49, so as to retain the spring 50 in position.

60 Mounted on and secured to the base by means of screws 53 are upstanding opposed plates 45 having slots 55, the crotches of which support the shaft 56 of a roll 57, around which the label strip 58 is wound. 65 Also mounted in bearings of the plates 54

are the pintles 59 of an impression roll 60, over which the label strip passes, when the labels of the druggists are being printed. One of the pintles 59 of the impression roll 60 carries a ratchet wheel 61, which is engaged by the dog 49.

The opposed plates 54 have registering slots 62, in which the pintles 63 of a printing cylinder or die 64 are mounted. This printing cylinder or die carries the name 75 of the druggist, and as the label strip passes between the cylinder or die 64 and the impression roll 60, the name of the druggist is applied to the label. Carried by the pintles of the die or cylinder 64 are 80 rings 65 to which springs 66 are connected. The springs 66 are in turn connected to the lugs 67, which project laterally from the opposed plates 54. By means of these springs the printing die or cylinder 64 is in contact with the label, as it passes between the die or cylinder and the impression roll 60. The opposed plates 54 have additional slots 68, which receive the pintles 69 of the inking roll 70. Plates 71 engage upon the pintles 69, and interposed between the plates and the upper ends of the slots 68 are coiled springs 72, which bear upon the plates, which in turn bear on the pintles, keeping the inking roll in contact with the printing die or cylinder 64, thereby supplying ink thereto. It will be observed that the label strip has its adhesive face downwardly as it leaves the roll, therefore the impression roll 60 will have a tendency to 100 feed the label strip through the printing mechanism, that is the printing mechanism for printing the druggist's name.

Pivoted upon a shaft 73 and movable therewith by means of the pin 74 is a lever 105 75, which has an upstanding arm 76, provided with a button or knob 77 on its upper end. The shaft 73 extends transversely of the base, and is mounted in bearings of the flange 2. This lever 75 carries the label impression member 5, and when an impression movement is imparted on the knob or button 77, the lever 75 oscillates, forcing the label impression plate upwardly against the label, the label being forced against the ribbon (which passes over the upper face of the label) while the ribbon is forced against the type of the cylinder or die 9, thereby causing an impression of the type on the label, and causing to be printed the name or title 115 of the medicine being purchased.

The label passes over the flanges 3, with its adhesive face downward, and mounted upon a pin 78 (which projects from one of the flanges 3) is a label feeding roll 79, 125 which has a rubber surface and bears against the adhesive face of the label strip, acting to feed the same transversely of the machine, when revoluble movement is imparted to the roll. Movable with the roll 79 130

is a ratchet wheel 80, with which a dog 81 engages. This dog is pivotally carried as at 82 in the notch 83 of the lever 75, and is under tension of the spring 84, which connects the dog to the flange 2 of the base. Obviously when the actuating lever 75 is tilted by depressing the knob 77, the arm of the lever 75 carrying the label impression plate 5 will move upwardly, and the dog 81 5 will move over the ratchet teeth of the label feed roll 79. When pressure on the actuating lever 75 is relieved, it will return to its normal position, and during this movement, the dog 81 will engage the teeth of the 10 ratchet 80 and impart a revolute movement to the label feed roll 79 in the direction of the arrow *a*, feeding the label transversely of the machine. The label will be fed sufficiently beyond the side of the machine, as to 15 permit the operator to grasp it, whereby it may be withdrawn sufficiently to permit the label to be cut off the requisite length.

Also rockable with the shaft 73 by means of the set screw 85 is an arm 86, one end of 20 which has a notch 87 to engage the lug 46. Also when the actuating lever 75 is tilted, the arm 86 is moved upwardly, imparting a vertical movement to the escapement detent 37, therefore when the escapement detent 37 25 moves upwardly, the dog 49 will move over the surface of the teeth of the ratchet wheel 61, then upon relieving pressure on the lever 75, the spring 42 will return the escapement detent to its normal position, causing the 30 dog 49 to engage one of the teeth of the ratchet wheel 61, and thereby impart an intermittent motion to the impression roll 60. The act of the impression roll 60 moving, will also feed the label strip through the 35 label guide extension 87. The movement of the label on the impression roll 60, will also cause the inking cylinder or die 64 to rotate, thereby imparting an impression of the name of the druggist upon the upper surface of the label. As previously stated when 40 the lever 75 is actuated, the impression plate 5 will move the label and the ribbon toward the type of the printing cylinder or die 9, causing an impression of the type on a label, hence printing the title or the name of the 45 medicine being purchased.

A lever 88 is pivotally mounted on the shaft 10 and has a handle 89 at one end, while connected to its lower end are the adjacent ends of a pair of springs 90. The remote ends of the springs 90 are connected at 91 to the dogs 43. A lug 92 projects laterally from the housing 7, and upon either side of which the lever 88 may be disposed. 50 If the lever 88 is on the right hand side of the lug 92, the coiled spring 90 on the right is under tension, thereby holding the dog 43 on the right in engagement with the ratchet wheel 19 on the right. Should the lever 88 55 be disposed on the left hand side of the lug

92, then the coiled spring 90 on the left will be under tension, and the dog 43 on the left in engagement with the ratchet wheel 19 on the left. The springs 90 have sufficient rigidity when not under tension, to tilt the dogs 70 from engagement with the ratchets 19. For instance when the spring 90 on the right is under tension, the spring on the left has sufficient rigidity to tilt the dog 43 from engagement with the ratchet wheel 19 on the left, and vice versa. When the dog 43 on the right is in engagement with the ratchet wheel 19 on the right, the ribbon is being unreeled from the roll 13, and reeled upon the roll 12, therefore when the lever 88 is 80 disposed on the left hand side of the lug or pin 92, the dog 43 on the left will engage the ratchet wheel 19 on the left, and cause a reverse movement of the ribbon.

As previously stated the flange 2 has a 85 depression 11 in its side, which is for the purpose of receiving the rectangular portion 93 (which carries a cutting blade 94) of the metal strip 95, which is secured at 96 to one side of the housing 7. This knife is disposed 90 in close proximity to the bottom of the depression 11, and immediately above the edge of the flange 2, where the flanges 3 unite therewith, so that when the label is fed sufficiently beyond the depression 11 to be 95 grasped and withdrawn, the label may be moved in contact with the cutting edge, and torn off, the cutting edge acting to facilitate the severing of the label.

It is obvious that the mechanism for printing the name of the druggist on the label may be eliminated if desired, and in this case the roll of labels to be carried by the machine may have the name of the druggist already printed thereon.

Where the label passes through the guide 87, an extension 99 is provided having a cam face 100, to guide or cam the label under the ribbon, when first inserting the label transversely of the machine. This extension 99 110 also constitutes a surface against which the feed roller 79 may bear, in order to feed the label transversely of the machine.

The invention having been set forth, what is claimed as being useful:

1. In a label printing and stamping machine, a casing, rolls mounted therein, an inking ribbon operatively winding from one to the other of said rolls, a printing cylinder in said casing, a label supporting and unreeling mechanism, an escapement detent operatively connected with one or the other of said rolls, a label feed carried by the escapement detent and operatively connected with the label supporting and unreeling mechanism, for feeding the label into the machine, a label printing die in the casing, and means for simultaneously impressing the label and the ribbon toward and upon the cylinder and actuating the escapement detent.

2. In a label printing and stamping machine, a casing having a rotating cylinder or die having type thereon for printing the names of stock medicines, ribbon rolls, a ribbon to operate from one to the other, movable means including a platen for moving a label below the ribbon toward the type of the cylinder to receive an impression, a label supporting and unreeling mechanism, an escapement detent for the rolls and operatively connected with one or the other, means operatively connecting the detent and the movable means, and means carried by the detent and operatively connected with the label supporting and unreeling mechanism for feeding the label between the platen and the ribbon, whereby the ribbon may be fed from one or the other of said rolls. 70

5. In a label printing and stamping machine, a casing, a rotating cylinder having type thereon for printing the names of different stock medicines, ribbon rolls, a ribbon to roll from one to the other of said rolls, said rolls having ratchet wheels, an oscillatory lever including a platen movable toward the type of the cylinder to print the label, a label supporting and unreeling mechanism having a ratchet wheel, an escapement detent operatively connected with either one of the ratchet wheels of the ribbon rolls for feeding the ribbon from one roll to the other, means operatively connecting the escapement detent and the lever, means carried by the escapement detent and operatively connected with the ratchet of the label supporting and unreeling mechanism for feeding the label between the platen and the ribbon, and means in the casing operatively connected with said lever for frictionally feeding the label between the ribbon and the platen upon the release of the impression movement of the platen. 100
- 20 25 30 35 40 45 50 55 60 65
6. In a label printing and stamping machine, a casing, a rotating cylinder having type thereon for printing the names of different stock medicines, ribbon rolls, a ribbon to roll from one to the other of said rolls, said rolls having ratchet wheels, an oscillatory lever including a platen movable toward the type of the cylinder to print the label, a label supporting and unreeling mechanism having a ratchet wheel, an escapement detent operatively connected with either one of the ratchet wheels of the ribbon rolls for feeding the ribbon from one roll to the other, means operatively connecting the escapement detent and the lever, means carried by the escapement detent and operatively connected with the ratchet of the label supporting and unreeling mechanism for feeding the label between the platen and the ribbon, and means for setting the escapement detent, whereby the ribbon may be fed from one or the other of said rolls. 75
- 20 25 30 35 40 45 50 55 60 65
7. In a label printing and stamping machine, a casing, a rotating cylinder having type thereon for printing the names of different stock medicines, ribbon rolls, a ribbon to roll from one to the other of said rolls, said rolls having ratchet wheels, an oscillatory lever including a platen movable toward the type of the cylinder to print the label, a label supporting and unreeling mechanism having a ratchet wheel, an escapement detent operatively connected with either one of the ratchet wheels of the ribbon rolls for feeding the ribbon from one roll to the other, means operatively connecting the escapement detent and the lever, means carried by the escapement detent and operatively connected with the ratchet of the label supporting and unreeling mechanism for feeding the label between the platen and the ribbon, and means for printing the name of the druggist on the label as it is fed. 95
- 20 25 30 35 40 45 50 55 60 65
8. In a label printing and stamping machine, a casing, a rotating cylinder having type thereon for printing the names of different stock medicines, ribbon rolls, a ribbon to roll from one to the other of said rolls, said rolls having ratchet wheels, an oscillatory lever including a platen movable toward the type of the cylinder to print the label, a label supporting and unreeling mechanism having a ratchet wheel, an escapement detent operatively connected with either one of the ratchet wheels of the ribbon rolls for feeding the ribbon from one roll to the other, means operatively connecting the escapement detent and the lever, means carried by the escapement detent and operatively connected with the ratchet of the label supporting and unreeling mechanism for feeding the label between the platen and the ribbon, and means for setting the escapement detent, whereby the ribbon may be fed from one or the other of said rolls. 125
- 20 25 30 35 40 45 50 55 60 65

oscillatory lever including a platen movable toward the type of the cylinder to print the label, a label supporting and unreeling mechanism having a ratchet wheel, an escapement detent operatively connected with either one of the ratchet wheels of the ribbon rolls for feeding the ribbon from one roll to the other, means operatively connecting the escapement detent and the lever, 5 means carried by the escapement detent and operatively connected with the ratchet of the label supporting and unreeling mechanism for feeding the label between the platen and the ribbon, and means for printing 10 the name of the druggist on the label as it is fed, and means in the casing operatively connected with said lever for frictionally feeding the label between the ribbon and the platen upon the release of the impression 15 movement of the platen, and means for setting the escapement detent, so that the ribbon may be fed from one or the other of said rolls.

9. In a label printing and stamping machine, a casing, rolls mounted therein, an inking ribbon to be wound from one to the other of said rolls, a printing cylinder in said casing, a label supporting and unreeling mechanism, an escapement detent operatively 25 connected with one or the other of said rolls, a label feed carried by the escapement detent and operatively connected with the label supporting and unreeling mechanism, for feeding the label into the machine, 30 a label printing die in the casing, and means for simultaneously impressing the label and the ribbon toward and upon the cylinder and actuating the escapement detent, and means within the casing and operatively 35 connected with the label and ribbon impressing means for additionally feeding the label upon the release of the impression movement of the label and ribbon impressing means, and means for setting the 40 escapement detent so that the ribbon may be fed from one or the other of said rolls.

10. In a label printing and stamping machine, a casing, a cylinder rotatably mounted therein and having type thereon for printing the names of different stock medicines, ribbon rolls having ratchet wheels and provided with a ribbon to wind from one or the other of said rolls, an oscillatory member including a platen below the ribbon for 50 moving a label and the ribbon toward the type of the cylinder, a vertically movable escapement detent, spring tensioning means therefor, dogs carried by the escapement detent to engage with one or the other of the ratchet wheels of the ribbon roll for feeding the ribbon from one roll to the other upon 55 downward movement of the detent when the member is tilted.

11. In a label printing and stamping machine, a casing, a cylinder rotatably mounted 65

ed therein and having type thereon for printing the names of different stock medicines, ribbon rolls having ratchet wheels and provided with a ribbon to wind from one or the other of said rolls, an oscillatory member including a platen below the ribbon for moving a label and the ribbon toward the type of the cylinder, a vertically movable escapement detent, spring tensioning means therefor, spring tensioned dogs carried by the escapement detent to engage with one or the other of the ratchet wheels of the ribbon rolls for feeding the ribbon from one roll to the other upon downward movement of the detent when the member is tilted. 75

12. In a label printing and stamping machine, a casing, a cylinder rotatably mounted therein and having type thereon for printing the names of different stock machines, ribbon rolls having ratchet wheels and provided with a ribbon to wind from one or the other of said rolls, an oscillatory member including a platen below the ribbon for moving a label and the ribbon toward the type of the cylinder, a vertically movable escapement detent, spring tensioning means therefor, dogs carried by the escapement detent to engage with one or the other of the ratchet wheels of the ribbon roll for feeding the ribbon from one roll to the other upon downward movement of the detent when the member is tilted, label supporting and unreeling means, means carried by the escapement detent and operatively connected with the label supporting and unreeling mechanism, for feeding the label between the platen and the ribbon, and means operatively connecting the escapement detent and said member. 90

13. In a label printing and stamping machine, a casing, a cylinder rotatably mounted therein and having type thereon for printing the names of different stock medicines, ribbon rolls having ratchet wheels and provided with a ribbon to wind from one or the other of said rolls, an oscillatory member including a platen below the ribbon for moving a label and the ribbon toward the type of the cylinder, a vertically movable escapement detent, spring tensioning means therefor, dogs carried by the escapement detent to engage with one or the other of the ratchet wheels of the ribbon roll for feeding the ribbon from one roll to the other upon downward movement of the detent when the member is tilted, a cylinder exteriorly of the casing and being operatively connected thereto and revoluble with the type carrying cylinder and having the names of the stock medicines thereon diametrically opposite those on the printing cylinders, and an indicator cooperating with the cylinder external of the casing for indicating when the name of the medicine to be printed is opposite the platen. 105

14. In a label printing and stamping machine, a casing, a cylinder rotatably mounted therein and having type thereon for printing the names of different stock medicines, ribbon rolls having ratchet wheels and provided with a ribbon to wind from one or the other of said rolls, an oscillatory member including a platen below the ribbon for moving a label and the ribbon toward the type of the cylinder, a vertically movable escapement detent, spring tensioning means, therefor, spring tensioning dogs carried by the escapement detent to engage with one or the other of the ratchet wheels of the 15 ribbon roll for feeding the ribbon from one roll to the other upon downward movement of the detent when the member is tilted, and means for setting the escapement detent, whereby one or the other of said spring tensioned dogs may be disengaged from its respective ratchet for permitting the ribbon to be fed from one or the other of said rolls.
15. In a label printing and stamping machine, a casing, a cylinder rotatably mounted therein and having type thereon for printing the names of different stock medicines, ribbon rolls having ratchet wheels and provided with a ribbon to wind from one or the other of said rolls, an oscillatory member including a platen below the ribbon for moving a label and the ribbon toward the type of the cylinder, a vertically movable escapement detent, spring tensioning means
- therefor, spring tensioned dogs carried by the escapement detent to engage with one or the other of the ratchet wheels of the ribbon rolls for feeding the ribbon from one roll to the other upon downward movement of the detent when the member is tilted, and means for setting the escapement detent, whereby one or the other of said spring tensioned dogs may be disengaged from its respective ratchet for permitting the ribbon to be fed from one or the other of said rolls, and friction means cooperating with the ribbon rolls to retard the action of the ribbon when unreeling from one roll to the other.
16. In a label printing and stamping machine, a casing, rolls mounted therein, an inking ribbon operating from one to the other of said rolls, a printing cylinder in said casing, a label supporting and unreeling mechanism, a label feed operatively connected with the label supporting and unreeling mechanism for feeding the label into the machine, a label printing die in the casing, and means for simultaneously impressing the label and ribbon toward and upon the cylinder, and means carrying the label feed and connecting with one or the other 60 of said rolls and being actuated by the label and ribbon impressing means for feeding the ribbon.

In testimony whereof I hereunto affix my signature.

HUGH F. HURST.
